2,363,402

DIRT SCRAPING APPARATUS

Gordon E. Daniels, Nashville, Tenn.

Original application December 2, 1938, Serial No. 243,562. Divided and this application April 5, 1943, Serial No. 481,820

8 Claims. (Cl. 37—126)

The present invention relates to dirt scraping apparatus, and has particular reference to apparatus of the type wherein a dirt accumulating body, having a scraping edge associated therewith, is dragged over the ground, the scraping edge biting into the surface of the ground and the forward movement of the body effecting movement of the scraped dirt upwardly into the body. When the scraper has received a capacity load, or less, as desired, it is raised to remove the scraper edge from contact with the ground and is then hauled to a point where it is desired to discharge the same. Such a dirt scraping apparatus is disclosed and claimed in my co-pending application Serial Number 243,562, filed December 2, 1938 and since issued as Patent No. 2,330,113, of which the present application is a division, and reference is hereby made to said application for a disclosure of the complete apparatus including mechanism not specifically disclosed herein.

The object of the present invention is to improve and simplify the hoisting means of a scraper or the like while maintaining a maximum amount of rigidity therein.

The manner in which the above and other objects of the invention are accomplished will be readily understood on reference to the following specification when read in conjunction with the accompanying drawings wherein:

Fig. 1 is an elevation view of the scraper apparatus embodying the present invention and shown in digging position;

Fig. 2 is a plan view of the scraping apparatus;

Fig. 3 is a sectional longitudinal elevation view of the scraping apparatus;

Fig. 4 is a transverse sectional view, taken along line 4—4 of Fig. 3;

Fig. 5 is a sectional view of the truck post and is taken along the line 5—5 of Fig. 4.

Referring to the drawings, the side walls 10 and 11 of the scraper body are connected at their upper ends to longitudinally extending beams 12 and 13, respectively, and at their lower ends to longitudinally extending beams 14. These side walls 10 and 11 are held in spaced relation by transversely extending beams 15, 16, 17, and 18.

The rear of the scraper is supported by pneumatic tired wheels 19, the axle of which is supported by brackets 20 extending from the beams 16 and 17.

A scraping blade 21, comprising the scraping edge, is supported from the transverse beam 18 in an inclined position and the cutting edge of

blade 21 extends below the remainder of the scraper body. Side cutter blades 9 are also provided on the forward lower edges of sides 10 and 11.

5 The forward end of the scraper is supported for vertical movement on a truck, generally indicated at 22, mounted on pneumatic tired wheels 23. The axle 24 for the wheels 23 has pivotally secured thereto a tongue 25 which is adapted to be drawn by a suitable tractor (not shown). A bearing block 26 (Figs. 3 and 4) is mounted within a well 27 formed centrally in the axle 24 and is movable about a horizontal transversely extending pin 28. Block 26 has a vertically extending socket formed therein to journal a depending bearing stud 29 formed on the bottom of a post 30.

As shown in Fig. 5, post 30 is substantially square in cross-section, having a pair of spaced 20 guide rails 31 and 32, formed on opposite sides thereof. These rails have slidably fitted therebetween, a pair of slide blocks 34 and 35, pivotally mounted on pins 36 and 37, respectively, secured in the beams 13 and 12, respectively, at 25 the forward ends thereof. It will thus be seen that blocks 34 and 35 form a sliding, rocking bearing connection or pivot device between the post 30 and the forward portion of the scraper body.

30 A pair of arcuately shaped links 39 are pivotally supported at their forward ends on opposite sides of the lower portion of the post 30 by a transversely extending pin 40 and are pivotally supported at their rear ends to forward extensions 41 of the bottom body beams 14 by coaxial pins 42. It will be seen from Fig. 2 that the links 39 diverge rearwardly toward the pins 42. Also, it will be seen from Figures 1 and 3 that the links 39 are bowed upwardly to permit the front wheel assembly, including axle 24 and wheels 23 to be moved to any desired position about the stud 29 without interfering with the links.

45 It will be noted that the above mentioned support and guide arrangement including the post 30 and the rocking slide bearings 34, 35, 36 and 37 between the post and the scraper body, and the links 39 provide a three point support in a vertical plane which, due to the spacing of the axes of the pins 36—37, 40 and 42 affords a maximum amount of rigidity commensurate with the strength of the various structural elements involved. It will also be noted upon inspection of Figs. 2 and 4 that the arrangement of links 50 39 and their pivots provides a three point sup-

port in a horizontal plane which affords a maximum amount of transverse rigidity for the articulated connection between the scraper body and the post 30.

The forward end of the scraper body is raised and lowered along the post 30 by means of a cable 43 wrapped around and anchored to a small diameter section 44 of a differential hoist drum 45 (Fig. 4). Drum 45 is journaled on a transversely extending shaft 46 supported by brackets 47 depending from the beams 12 and 13. Cable 43, after leaving the small diameter section 44 15 passes around a pulley 48 rotatably mounted on a bracket at the top of post 30 and is then led around a pulley 49 rotatably mounted in a pulley block 50. Block 50 is pivotally mounted on a pin 51 extending between the beams 12 and 13. On leaving pulley 49, cable 43 is passed over a pulley 52, also rotatably mounted at the top of post 30 and is thence wrapped around and anchored to a large diameter section 53 of the drum 45. A second cable 54 is wrapped around and anchored to a second large diameter section 55 of drum 45 and thence passes under a pulley 56 rotatably mounted in an opening 30' 20 extending through post 30. The cable 54 is preferably operated by a power driven winch (not shown) provided on the tractor and under control of the tractor operator. When the cable 54 is drawn by the winch the drum 45 will be rotated so as to cause a differential action upon the cable 43 to shorten the length of the same and thus draw the scraper body upwardly along the post 30.

The above mentioned hoist mechanism permits a substantial raising and lowering movement to be applied to the scraper body with a minimum rocking movement applied to the post 30. Therefore, the weight of the scraper apparatus is applied substantially longitudinally of the post 33 throughout the travel of the bearing blocks 34 and 35, thereby reducing complicated stresses occurring in the post and enabling the same to be made as light as possible while forming a simple arrangement of levers to effect the hoisting operation. Furthermore, this hoist mechanism forms a compact arrangement resulting in a reduction of weight of the apparatus.

It is to be understood that, while I have herein described and illustrated a preferred form of my invention, it is not limited to the precise construction as herein described but includes within its scope whatever changes may come within the spirit of the appended claims.

What I claim as new and desire to secure by Letters Patent is:

1. In a scraping apparatus, the combination with a load carrying body; of means for supporting said body at one end thereof comprising a movable truck including a support; a link member pivotally connected between said support and said body, a rocking slide connection between said support and said body and spaced from the pivotal connections of said link member, said rocking slide bearing being adapted to guide said end of said body relative to said support in a substantially vertical direction, and means for moving said end of said body relative to said support.

2. In a scraping apparatus, the combination with a load carrying body; of means for supporting said body at one end thereof comprising a movable truck including a support; a link member pivotally connected between said support and said body, a pivot device carried by

said body above the pivotal connection between said link member and said support, means forming a guide-way on said support for guiding said pivot device along said support, and means for moving said end of said body along said support.

3. In a scraping apparatus, the combination with a load carrying body; of means for supporting said body at one end thereof comprising a movable truck including a support; a pair of link members pivotally connected between said support and said body and converging relative to each other toward said support, a pivot device carried by said body, means forming a guide-way on said support for guiding said pivot device along said support, and means for moving said end of said body relative to said support.

4. In a scraping apparatus, the combination with a load carrying body; of means for supporting said body at one end thereof comprising a movable truck including a support, supporting wheels, an axle for said wheels, and means pivotally connecting said axle to said support for movement about a vertical axis; a pair of link members pivotally connected between said body and said support adjacent the lower ends of said body and said support respectively, and below the tops of the peripheries of said wheels, said links being bowed upwardly whereby to permit movement of said axle and said wheels about said first mentioned pivotal connection and under said links, means movably and pivotally securing said body to said support adjacent the upper end of said body for guiding said end of said body relative to said support in a substantially vertical direction, and means for moving said end of said body relative to said support.

5. In a scraping apparatus, the combination with a load carrying body; of means for supporting said body at one end thereof, comprising wheels, an axle for said wheels, an upwardly extending post connected to said axle, a link member pivotally connected between said body and said post, a rocking slide connection between said post and said body, and spaced from the pivotal connection of said link member, and means for moving said one end of said body along said post.

6. In a scraping apparatus, the combination with a load carrying body; of means for supporting said body at one end thereof, comprising wheels, an axle for said wheels, an upwardly extending post connected to said axle, a pair of link members pivotally connected between said body and said post and converging relative to each other toward said post, a rocking slide connection between said post and said one end of said body in spaced relation to the pivotal connection between said post and said link members; and means for moving said end of said body along said post.

7. In a scraping apparatus, the combination with a load carrying body; of means for supporting said body at one end thereof comprising a movable truck including a support; a pair of link members pivotally connected between said body and said support and converging relative to each other toward said support, rockable bearings movable along said support in a substantially vertical direction, a pair of supporting members rigidly connected to said body and connected to said bearings, said members converging relative to each other toward said support, and means for moving said bearings along said support.

8. In a scraping apparatus, the combination with a load carrying body; of means for supporting said body at one end thereof comprising a truck including a support; a link member pivotally connected between said body and said support, a rocking slide connection between said body and said support and spaced from said link

member, and means for moving said one end of said body substantially vertically along said support comprising sheaves on said body and said support respectively, and a hoist cable passed around said sheaves.

GORDON E. DANIELS.
